UNITED STATES PATENT OFFICE.

CEPHAS I. SHIRLEY, OF GLEN RIDGE, AND FREDERICK WALTER MUELLER, OF NEWARK, NEW JERSEY, ASSIGNORS TO TABOR SASH FIXTURE CO., A CORPORATION OF NEW JERSEY.

SASH-HINGE FIXTURE.

1,135,407.

Specification of Letters Patent. Patented Apr. 13, 1915.

Application filed October 1, 1913. Serial No. 792,728.

To all whom it may concern:

Be it known that we, CEPHAS I. SHIRLEY and FREDERICK WALTER MUELLER, citizens of the United States, residing at Glen Ridge and Newark, in the county of Essex and State of New Jersey, respectively, have invented certain new and useful Improvements in Sash-Hinge Fixtures; and we do hereby declare the following to be a full, 10 clear, and exact description of the invention, such as will enable others skilled in the art to which it appertains to make and use the same, reference being had to the accompanying drawings, and to characters of reference marked thereon, which form a part 15 of this specification.

This invention is in the nature of improvements in that class of hinge-fixtures for windows having a sash or sashes which 20 are mounted in the window-frame so as to be adapted to move vertically and also to swing horizontal when the sash has been raised by the manipulation of the hinge-fixture; and, the present invention has reference, more 25 particularly, to a novel and simply-constructed hinge-fixture comprising a pair of pivotally and slidably connected hinge-leaves, one of which is secured to the window-sash and the other to the window- 30 frame, and the hinged or pivoted hinge-leave being provided with an operating means interposed between the two hinge-leaves in such a manner, that by the manipulation of a lever, the one hinge may be re- 35 ciprocated upon the hinge-pin with relation to the other hinge-leaf.

The present invention has for its principal object to provide a hinge-fixture of the general character hereinafter set forth and to 40 simplify the general construction of the same, with a view of reducing the parts of the fixture to a minimum.

With the objects of the invention in view, the invention consists, primarily, in the 45 novel hinge-fixture hereinafter set forth; and, the invention consists, furthermore, in the general arrangements and combinations of the several devices and parts, comprising the fixture, and all of which will be more 50 particularly described in detail in the following specification, and then finally embodied in the clauses of the claims which are appended to and which form an essential part of said specification.

The invention is illustrated in the accompanying drawings, in which:—

Figure 1 is an inside elevation of a window equipped with a hinge-fixture illustrating one embodiment of the principles of the present invention. Fig. 2 is a fragmentary 60 transverse sectional representation of a window frame and sash, on an enlarged scale, showing the sash in its lowered and closed relation within the opening of the frame, showing the relative positions of the parts 65 of the hinge-fixture applied to the frame and sash; and Fig. 3 is a similar representation of the frame and sash, and the hinge-fixture, said view, however, showing the parts of the fixture in their manipulated relation for lifting or raising the sash, prior 70 to its being swung horizontally. Fig. 4 is a face view of the hinge-fixture, detached from the frame and sash; Fig. 5 is a vertical section of the same, said section being 75 taken on line 5—5 in said Fig. 4, looking in the direction of the arrow *x*; and Fig. 6 is a sectional representation of the hinge-fixture, said section being taken on line 6—6 in said Fig. 5, looking in the direction of the arrow 80 *y*. Fig. 7 is a horizontal section of the hinge-fixture, said section being taken on line 7—7 in Fig. 4; and Fig. 8 is a similar section of the fixture, said section being taken on line 8—8 in said Fig. 4. 85

Similar characters of reference are employed in all of the said above described views, to indicate corresponding parts.

Referring now to the figures of the drawings, the reference-character 1 indicates the 90 lower horizontal sill, 2 an upper horizontal jamb or head, and 3, 3, the vertical side jambs of a window frame, all providing an opening in which is adapted to move vertically, and also to swing horizontally, a window sash. The sash comprises two vertical 95 side rails or stiles 4, 4, a top rail 5, and a bottom rail 6, the sash, as has been stated, when closed in the opening of the window frame, being adapted to be brought into its 100 lowered and locked relation, as indicated in Fig. 2, and to be brought into its raised relation, as represented in Fig. 3, whereby the said sash may be swung horizontally into its open position, relative to the window frame. 105

As illustrated in the cross-sections represented in Figs. 2 and 3 of the drawings, the horizontal sill 1 is made with a channel or

groove, as 7, and an upwardly projecting bead or projection 8, both said channel or groove 7 and said bead or projection 8 extending the entire length of the sill, and said 5 bead or projection 8 providing an alining stop for the purposes to be presently more fully specified. The lower portion of the window sash, that is the bottom rail 6 and the ends of the vertical side rails or 10 stiles 4, is made with a laterally extending and downwardly projecting tongue 9 and a laterally extending groove 10 which respectively register with the channel or groove 7 and the bead 8 when the sash has 15 been closed and lowered, so as to provide a weather-tight joint as will be clearly evident from an inspection of said Fig. 2. Another purpose of the bead or projection 8 and tongue 9 is, in closing the sash from its 20 opened position to its closed position, the lower surface of the tongue 9 being located in a plane below the plane of the upper surface of the bead 8, these two elements will be brought into arresting engagement, while 25 the bead 8 acts as a stop, so that the window sash and hinges can not be strained, and the sash will be brought into a perfect alined relation within the opening of the window-frame, as will be evident, and when the sash 30 is lowered in the manner to be hereinafter described, a perfectly locked and tight relation of the parts 7 and 8 with the parts 9 and 10 will result.

Referring now to Fig. 1 of the drawings, 35 the reference-characters 11 and 12 represent the two leaves of a plain hinge which are secured to the opposing upper parts of the pivot-stile 4 of the sash and the adjacently located side-rail 3 of the window frame, the 40 said leaves 11 and 12 being pivotally connected by means of a pivot-pin, in the usual manner. It will be understood, however, that the said pivot-pin connects the two 45 leaves 11 and 12 in a manner so that the leaves have a sliding relation, vertically, to each other, and that the sash will be capable of being rotated horizontally and may also be moved vertically up and down, in the opening of the window frame. More 50 than one of such hinges may be applied to the sash and frame, according to the height, width and other conditions of the window sash and frame.

In connection with the hinge, a hinge- 55 fixture of the general construction to be presently more fully described may be used, said hinge-fixture serving as the other hinge for raising and lowering the sash, and for swinging the sash horizontally after it has 60 been raised. This raising and lowering hinge-fixture consists, essentially, of a pair of hinge-leaves, as 13 and 14, the leaf 13 being cut away, as at 15, and being provided with tubular knuckles, as 16, in the 65 tubular part of which is slidably disposed

the lower end-portion of a pivot-pin 17. The other hinge-leaf 14 is cut away, as at 18 and 19, and is provided with a pair of tubular knuckles 20 and 21. The tubular portions of said knuckles 20 and 21 are vertically in alinement with each other, and the said pivot-pin 17 has its other end-portion fixed within said tubular members 20 and 21 against displacement therefrom, said portion of the pin 17 extending also across the open or cut away part 19. Pivotally mounted upon this part of the pivot-pin 17 is a stud-carrying block 22, having a tubular part 23 which extends into the said cut away part 19, and is pivotally mounted upon that part of the pin 17 which extends across said cut-away part 19.

The member 16 of the leaf 13 is provided with an opening, as 24, which forms a bearing-portion in which is rotatably arranged the part 25 of a pin, one portion, as 26, of said pin being suitably driven into an eccentric or cam-body 29 of an operating handle or lever 28, and the other end-portion of said pin being screw-threaded, as at 27, and being provided with a nut 30, for operatively connecting the parts to said member 16, substantially in the manner illustrated in Fig. 5 of the drawings. The previously-mentioned block 22 is provided with a suitable opening, as 31, in which is fixed a stud 32, the one end of said stud being headed, as at 33, and projecting beyond the front face of said block 22, as shown. Pivotally mounted upon said projecting portion of said stud 32 is the perforated end-portion 35 of a link 34, said link being provided in its opposite end-portion with a large opening, as 26, conforming to the marginal configuration of the previously-mentioned eccentric or cam-body 29 of the handle or lever 28, in the manner clearly represented in Figs. 2, 3, 4, 5 and 7 of the drawings.

The operation of the sash-lifting and lowering mechanism will readily be understood from the foregoing description, and from an inspection of the several figures showing the several devices, and need, therefore, not be further described; and, the manner of raising and lowering the window-sash, for swinging it into its open relation with the window frame, or for locking the sash when closed will be particularly understood from an inspection of Fig. 2 of the drawings.

We are fully aware, that various changes may be made in the general arrangements and combinations of the several devices and parts, as well as in the details of the description of said parts, without departing from the scope of the present invention as set forth in the foregoing specification, and as defined in the clauses of the claim which are appended thereto. Hence, we do not limit our present invention to the exact

arrangements and combinations of the various devices and parts as described in the said specification, nor do we confine ourselves to the exact details of the construction of the said parts, as illustrated in the accompanying drawings.

We claim:-

1. A fixture for windows having a sash which is mounted in the frame to move vertically and also swing horizontally comprising a hinge having a leaf adapted to be secured to the frame and a leaf adapted to be connected with the sash, said leaves being pivotally connected by means of a pivot-pin, and one of said leaves being slidably mounted upon said pin, a stud-carrying block also mounted upon said pivot-pin, and means interposed between said slidably mounted leaf and said stud-carrying block for producing the sliding relation of said leaves.

2. A fixture for windows having a sash which is mounted in the frame to move vertically and also swing horizontally comprising a hinge having a leaf adapted to be secured to the frame and a leaf adapted to be connected with the sash, said leaves being pivotally connected by means of a pivot-pin, and one of said leaves being slidably mounted upon said pin, a stud-carrying block also mounted upon said pivot-pin, a cam-lever pivotally connected with said slidably mounted hinge-leaf, and means interposed between said cam-lever and said stud-carrying block for producing the sliding relation of said leaves.

3. A fixture for windows having a sash which is mounted in the frame to move vertically and also swing horizontally comprising a hinge having a leaf adapted to be secured to the frame and a leaf adapted to be connected with the sash, said leaves being pivotally connected by means of a pivot-pin, and one of said leaves being slidably mounted upon said pin, a stud-carrying block also mounted upon said pivot-pin, a lever pivotally connected with said slidably mounted hinge-leaf, an eccentric or cam-shaped member connected with said lever, and a link interposed between said eccentric or cam-shaped member and said stud-carrying block for producing the sliding relation of said leaves.

4. A fixture for windows having a sash which is mounted in the frame to move vertically and swing horizontally comprising a hinge having a fixed leaf adapted to be secured to the frame and a movable leaf adapted to be connected with the sash, said movable leaf being provided with a pintle-receiving knuckle, and said fixed leaf being provided with a pair of pintle-receiving knuckles having a stud-clock receiving space

between them, a pintle in the pintle-receiving knuckles of said leaves, said pintle extending across said stud-block receiving space, a stud-block, said block having a pintle-receiving knuckle extending into said stud-block receiving space and mounted upon said pintle, and means interposed between said movable hinge-leaf and said stud-block for producing the sliding relation of said leaves.

5. A fixture for windows having a sash which is mounted in the frame to move vertically and also swing horizontally comprising a hinge having a fixed leaf adapted to be secured to the frame and a movable leaf adapted to be connected with the sash, said movable leaf being provided with a pintle-receiving knuckle, and said fixed leaf being provided with a pair of pintle-receiving knuckles having a stud-block receiving space between them, a pintle in the pintle-receiving knuckles of said leaves, said pintle extending across said stud-block receiving space, a stud-block, said block having a pintle-receiving knuckle extending into said stud-block receiving space and mounted upon said pintle, a cam-lever pivotally connected with said slidably mounted hinge-leaf, and means interposed between said cam-lever and said stud-carrying block for producing the sliding relation of said lever.

6. A fixture for windows having a sash which is mounted in the frame to move vertically and also swing horizontally comprising a hinge having a fixed leaf adapted to be secured to the frame and a movable leaf adapted to be connected with the sash, said movable leaf being provided with a pintle-receiving knuckle, and said fixed leaf being provided with a pair of pintle-receiving knuckles having a stud-block receiving space between them, a pintle in the pintle-receiving knuckles of said leaves, said pintle extending across said stud-block receiving space, a stud-block, said block having a pintle-receiving knuckle extending into said stud-block receiving space and mounted upon said pintle, a lever pivotally connected with said slidably mounted hinge-leaf, an eccentric or cam-shaped member connected with said lever, and a link interposed between said eccentric or cam-shaped member and said stud-carrying block for producing the sliding relation of said lever.

In testimony, that we claim the invention set forth above we have hereunto set our hands this seventeenth day of September, 1913.

CEPHAS I. SHIRLEY.

FREDERICK WALTER MUELLER.
